HENRY D. SCHMIDT, OF NEW YORK, N. Y.

EMBOSSING-MACHINE.

1,241,152.

Specification of Letters Patent. Patented Sept. 25, 1917.

Application filed June 10, 1916. Serial No. 102,809.

To all whom it may concern:

Be it known that I, HENRY D. SCHMIDT, a subject of the Emperor of Germany, residing at Astoria, in the borough of Queens, 5 city of New York, county of Queens, and State of New York, have invented certain new and useful Improvements in Embossing-Machines, of which the following is a specification, reference being had therein to the accompanying drawings, which form a part thereof.

My invention relates to embossing machines and more particularly to a machine of this type adapted for use in finishing textiles 15 or similar products.

Heretofore, in machines of this type the pressure between the pattern roller and its opposed platen roller has been developed by the application of pressure to 20 the arbors of the pattern roller. This practice results in the springing of the pattern roller toward the center thereof in a manner to cause unequal pressure along the line of engagement of the pattern and platen 25 rollers with a resultant variance in the height of the embossed portions of the textile at different points thereof. In this type of machine it is necessary to use a heated pattern roller and upon the completion of 30 the run of the machine it is necessary to separate the pattern and platen rollers to avoid burning of the facing upon the latter. In machines heretofore used, this separation has been secured by moving the pattern roller 35 away from the platen roller by means of set screws operative at opposite ends of said platen roller, which set screws are used to develop the pressure between the rollers, thus necessitating a re-adjustment of the 40 pressure when re-setting the machine for a subsequent run.

A machine made in accordance with my invention is so constructed that the stresses developing pressure between the pattern and 45 the platen rollers will be applied to the former by the latter along substantially the entire length thereof so as to minimize a tendency of the pattern roller to spring away from the platen roller, a counter stress being 50 applied along a limited portion of the pattern roller adjacent the center thereof at all times while the machine is operating so as to correct any slight distortion of the pat-

tern roller adjacent the center. While the means developing the pressure stresses and 55 the means developing the counter-stresses operate simultaneously upon the pattern roller, each is provided with its own operating and adjusting mechanism so that the relative pressures upon the opposite sides 60 of the platen roller may be regulated to meet different conditions of use in the machine.

The machine is also so constructed that while it may be set for a certain pressure, the platen roller is so supported that it may receive movement toward or from the pattern roller without disturbing the adjustment for pressure, thus permitting the rapid separation of the pattern and platen rollers, and their return to their former operative relation without the necessity for re-adjusting the machine for pressure. The means for imparting the desired throw to the platen roller may also be used to impart a variable movement to said roller, so that even though 75 the machine be set for a certain pressure by the pressure adjustment mechanism, nevertheless, this pressure may be varied independently of said last named mechanism. The counter-pressure roller is also provided 80 with a throw-off mechanism operative independently of the throw-off mechanism of the platen roller, by means of which said counter-pressure roller may be rapidly moved into and out of engagement with the pattern 85 roller without disturbing the adjustment for pressure, said throw-off mechanism operative upon said counter-pressure roller being capable of developing variable pressure through said roller independently of the 90 mechanism by means of which the machine may be set for a definite pressure as to said roller.

The platen roller, pressure roller and counter-pressure roller are preferably all 95 driven at the same peripheral speed, each of said rollers being removably mounted in the machine in a manner to permit the removal of the several rollers and the substitution therefor of other rollers bearing different designs and having different dimensions.

I also provide a special heating attachment for the pattern roller which will have the effect of distributing the heat along substantially the entire length of the roller in 105 a manner to secure uniform heat conditions

throughout the roller and avoid the necessity for constant attention to the heating attachment and frequent movement thereof to avoid over or under heating of the roller in 5 spots. I also provide a pressure developing mechanism which will insure an absolutely parallel movement of the platen roller, thus facilitating the rapid setting of the machine for the desired pressure and permitting frequent 10 re-adjustment of the machine without likelihood of a loss in the alinement of the platen roller.

The invention consists primarily in an embossing machine embodying therein the 15 novel features of construction and combination of parts hereinafter set forth and described and more particularly pointed out in the claims hereto appended.

Referring to the drawings:—
20 Figure 1 is a perspective view from the feed end of a machine embodying my invention;

Fig. 2 is a perspective view from the delivery end of said machine;

25 Fig. 3 is a vertical section through the upper portion of the machine, parts thereof being broken away;

Fig. 4 is a detail view of one of the supports for the platen or pressure roller; and

30 Fig. 5 is a detail view of a part of the throw-off mechanism for the counter-pressure roller.

Like letters refer to like parts throughout the several views.

35 In the embodiment of my invention shown in the drawings, the pattern roller carrying the engraved embossing plate is shown at 10, the arbors of said roller being mounted in suitable saddles and stirrups, indicated at 40 11, to facilitate the mounting and removal of this roller. The roller 10 is mounted in fixed bearings, the pressure required in the operation of the machine being developed by the movement of the pressure or platen 45 roller and the counter-pressure roller toward said roller 10. Mounted below the roller 10 is a platen or pressure roller 12 which is provided with the usual facing for the purpose of permitting the desired impression to 50 be made upon the cloth by the plate upon the roller 10. To permit the movement of the roller 12 toward and from the roller 10, I mount the arbors of said roller in vertically reciprocatory housings 13, said housings being actuated by means of oppositely disposed feed screws 14 each of which carries a worm wheel 15, acted upon by the worm shaft 16, provided with a hand wheel 17. By this construction both arbors of the 60 roller 12 may have simultaneous movement to the same extent imparted thereto, thus insuring an absolutely parallel movement of the said roller 12 and uniformity in the application of pressure throughout the entire 65 length of the said rollers 10—12. The uti-

lization of a worm shaft and worm wheels also permits nicety in the regulation of the pressures.

To permit the movement of the roller 12 toward and away from the roller 10, without disturbing the adjustment for pressure secured by the mechanism above referred to, I make the housings 13 in two sections and mount in one of these sections, a cam shaft 18, the cams 19 upon which operate on the other sections in a manner to cause the raising or lowering of the section in which the arbors of the roller 12 are mounted. Mounted upon said cam shaft is a ratchet wheel 20 acted upon by a pawl 21 so as to permit the cams 19 to be set in any adjusted position, thus permitting a variance in the pressure for which the machine is set by the screws 14 by means of said cams. The shaft 18 carries an operating handle 22. The pawl 23 is controlled by the release mechanism 24. The said cam shaft 18 and its appurtenances constitute a throw-off mechanism by means of which the rollers 10—12 may be quickly separated when the machine is not operating, thus avoiding likelihood of the burning of the facing upon the roller 12 through a continued contact with the heated plate upon the roller 10.

Power is applied to the machine through the gear train 24 acting upon the roller 12 and the gears 25 and 26 carried by the arbors of said roller 12 and the roller 10 respectively. At 27 I have shown a pulley carried by the main power shaft 28 of the 100 machine.

While the manner of advancing the roller 12 toward the roller 10 will minimize the tendency of the latter to spring out of true, nevertheless, with the operation of the machine, that portion of said roller 10 remote from its arbors will yield from the resistance encountered as the cloth passes between the center thereof and the platen roller. To avoid this condition, I provide a short roller 29 through which a pressure counter to that developed by the roller 12 is applied to a short section of the roller 10 adjacent the center thereof only. By using a short roller 29, or one the length of which is considerably less than that of the roller 10, I localize the counter stresses, and restrict them to that portion of the roller 10 which is subject to distortion, or loss of alinement. The roller 29 is mounted between the arms 30 of a yoke, said arms being pivotally mounted at 31 in the frame of the machine and said yoke being provided with a stem 32, the said roller being mounted between the points of pivotal support 31 and the said stem so that a downward pressure upon said stem will cause the exertion of the desired pressure upon the roller 10 by the roller 29. The roller 29 is provided with a face similar to that used upon the roller 12. One arbor of 130

the roller 29 is connected by means of a universal joint 33 with a driving shaft 34, the gear 35 upon which shaft is in mesh with the gear 26 so as to impart positive rotary movement to said roller 29. 5

Carried upon standards 36 is a shaft 37 upon which the yoke 38 is pivotally mounted. Said shaft carries at each end thereof cams 39 by means of which the yoke 38 may be 10 raised or lowered. The shaft 37 centrally thereof is adapted to be engaged by the stem 32 so that when the said shaft is turned by means of the hand wheel 40, it and the yoke 38 will be raised and substantially simultaneously the stem 32 will be raised carrying 15 with it the roller 29 so as to bring said roller out of engagement with the roller 10. The yoke 38 has mounted therein a hand screw 41 adapted to bear upon the stem 32 in a 20 manner to force the roller 29 into engagement with the roller 10 with the resultant development of the desired pressure to withstand the distortion strains developed upon the roller 10.

25 The shaft 37 and the cams 39 may be used to separate the counterpressure roller 29 from the pattern roller 10 or bring said rollers into the desired pressure relation without disturbing the adjustment for pressure; 30 or the degree of pressure for which the said counter-pressure roller is set by means of the hand screw 41. Furthermore, the pressure exerted by the roller 29 may be varied by means of said cams and said shaft independently of and without disturbing, the 35 adjustment for pressure secured through the said screw 41.

The roller 10 is made of hollow metal, heat being applied to the interior of the roller for 40 the purpose of bringing the engraved embossing plate or cylinder carried by said roller, to the desired temperature. One end of the cylinder is open as shown in Fig. 1 to permit the insertion of an elongated burner 45 tube 42 within said cylinder. The outer end of this tube 42 is forked, one arm thereof, as 48 being connected to a gas pipe 44 and the other arms 45 being connected with the air pipe 46 or other means for delivering a medium to said tube in conjunction with the 50 gas for the purpose of developing a combustible mixture which will develop heat of the desired intensity.

The burner tube 42 merely rests upon the 55 bottom of the opening in the roller 10 so that said roller will turn freely without the necessity for supplying swiveling connections between the burner and the connections from which it receives its combustible mixture. 60 To secure the desired distribution of heat throughout the embossing plate upon the roller, the tube 42 is made of substantially the same length as the said roller and is provided with a plurality of small jet openings 65 distributed along the length thereof.

To permit the quick separation of the arms 43-45 from the gas and air supply pipes 44-46, the connections between said arms and said pipe consist of a flexible rubber tubing so that by disconnecting said tubing 70 the burner in its entirety may be withdrawn from the said cylinder.

At the feed end of the machine I provide forked arms 47 adapted to receive the arbors of a roll carrying the textile and arranged 75 between said supports and the rollers 10-12 is a plurality of tensioning and guiding rollers 48 which serve to hold the textile taut as it passes between the said rollers. If desired a spraying pipe 49 may be mounted 80 below the rollers 48 so as to dampen the textile slightly before it passes between the said roller.

Mounted upon pivotal arms 50 is a guard roller 51 adapted to bear upon the roller 12 85 to facilitate the threading of the textile through the machine while the machine is running without endangering the hand of the operator.

At the delivery end of the machine, I provide a roller 52 over which the cloth passes after leaving the rollers 10-12, which roller 52 is driven by means of the pulley 53 and belt 54 driven from the shaft of the intermediate gear of the train 24. 90

Carried by the standards 55 at the delivery end of the machine are brackets 56 in which a weighted roller may be mounted for the purpose of permitting the cloth to be held taut between the roller 52 and the embossing rollers. Also carried by the standards 55 are brackets 57 adapted to receive a table upon which the cloth after being embossed may fall in folds. 100

The operation of the herein described machine is substantially as follows:— 105

A pattern roller 10 having the desired design thereon, being mounted in the machine, the saddle and stirrup for the arbors of said roller are firmly connected so as to prevent 110 vertical displacement of the said roller. The operating handle 22 is then pulled downwardly so as to set the cams 19 with the high point thereof so positioned as to advance the platen roller 12 toward the roller 10. Thereafter the hand wheel 17 is used to turn the worm shaft 16, and the screws 14 through the worm wheels 15 carried thereby, thus simultaneously raising both housings 13 and moving the roller 12 in its entirety toward 115 the roller 10. By applying power simultaneously to both housings 13 by the same actuating mechanism, the roller 12 will receive a parallel movement without likelihood of a loss of alinement or development of variable 120 pressures at the opposite ends thereof. In this manner, the machine may be set for a certain pressure to be maintained during a long run thereof which pressure may be relieved or varied without disturbing the ad- 125 130

justment secured by means of the screws 14 and their actuating mechanism.

Either before or after the setting of the machine for pressure by means of the screws 14, the shaft 37 is so turned by means of the hand wheel 40 as to cause the cams 39 to bring the yoke 38 to its lowermost position. Thereafter the hand screw 41 is turned to force the stem 32 of the yoke 30 downwardly 10 until the roller 29 exerts sufficient pressure upon the pattern roller 10 to counteract any tendency of the said roller to spring away from the roller 12 at the center thereof. The pressure exerted by the roller 29 is localized 15 adjacent the center of the roller 10 since a short roller 29 has less tendency to spring than a long roller and pressure applied along the top of the roller 10 for a short distance upon opposite sides of the center thereof, 20 will serve to effectively counteract a tendency of said roller to spring at any point intermediate the arbors thereof. I lay particular stress upon the use of a short roller 29 because in practice I have found this construction to be highly effective in preventing 25 distortion of the pattern roller, and in fact, an essential characteristic of the pressure developing mechanism in the machine.

The hand screw 41 may be used to set the 30 roller 29 for a certain pressure, which pressure may be relieved or varied by means of the cams 39 without disturbing the adjustment secured by means of the said screw 41.

The machine having been set in the manner described, the lever 22 is raised, the pawl 21 being released to permit the rotation of the shaft 18 and its cams 19, so as to permit the roller 12 to drop out of engagement with the roller 10. At the same time the hand 40 wheel 40 is turned so as to actuate the cams 39 in a manner to raise the shaft 37 and the stem 32 and move the roller 29 away from the upper radius of the roller 10 and out of operative engagement therewith.

45 The burner 42 is then inserted in the roller 10 and power is applied to the machine until the said roller has been properly heated, the paper or other facing of the rollers 12 and 29 not being in engagement with the said roller 10 by reason of the actuation of the respective throw-out mechanisms by means of the lever 22 and wheel 40. The burner 42 remains in this position during the entire run of the machine, any modification of the heating effect being secured by means of the control of the fuel supply as distinguished from the physical movement of the burner itself. By using a burner having jet openings distributed along the 55 entire length thereof, which length is substantially the same as that of the pattern cylinder, uniform distribution of the heat throughout the entire plate is secured.

60 When the roller 10 is properly heated the lever 22 is used to raise the roller 12 and

bring it into engagement with the roller 10, developing that pressure for which the machine was previously set by means of the screws 14. At the same time the hand wheel 40 is turned so as to draw the yoke 38 downwardly and force the roller 29 into engagement with a point diametrically opposite the line of engagement between the rollers 10 and 12, developing that counter-pressure for which the machine has been 70 previously set by means of the hand screw 41.

The end of the cloth is then threaded over and about the tensioning and guide rollers 48 and beneath the guard roller 51, this guard roller initiating the feed of the cloth 80 and preventing the hand of the operator being drawn between the platen and pattern rollers. As the cloth is embossed and leaves the rollers 10 and 12, it passes over the delivery roller 52 which is driven at substantially the same peripheral speed as the rollers 10 and 12 so as to prevent the formation of slack between it and said rollers. A table to receive the cloth may be mounted upon the brackets 57. If desired no such 90 table need be used; and in this case the said brackets may be turned within the frame of the machine so as not to interfere with the workman.

95 By providing rollers 12 and 29 with independently operative means by which they may be set to develop the desired pressure, the pressure and counter-pressure to which the roller 10 is subjected may be so controlled as to secure the desired operative 100 effect upon the roller 10 and the relative pressure exerted by said rollers 12 and 29 may be so proportioned as to avoid subjecting the roller 10 to excessive pressures.

So long as the machine is running, there is 105 no tendency of the roller 10 to burn or char the facing upon the rollers 12 and 29, but upon the stoppage of the machine there is such a tendency. To permit the rapid separation of the rollers 12 and 29 from the 110 roller 10, the throw-off mechanisms heretofore described are provided. These throw-off mechanisms when the machine is stopped should be immediately actuated and since the stoppage of the machine is frequent, it 115 is desirable to provide such mechanisms as may be operative to so separate the rollers and restore them to their operative relation without the necessity for re-adjusting the pressure of the machine each time said rollers are restored to the operative relation. In the machine heretofore described to move the roller 12 out of engagement with the roller 10, it is merely necessary to release the pawl 21 and raise the lever 22, the cam 125 shaft 18 carrying said lever, simultaneously turning both cams 19 in a manner to permit the section of the housings 13 in which the roller 10 is mounted to drop to an extent sufficient to cause the roller 12 to move out 130

of engagement with the roller 10. The roller 29 is moved out of engagement with the roller 10 by merely turning the hand wheel 40, the cams 39 carried by the shaft 37 simultaneously raising said shaft, the yoke 38, the screw 41 carried thereby and the stem 32 of the yoke 30 carrying said roller 29. It will be observed that the actuation of the cams 19 and 39 does not disturb the adjustment of the screws 14 or 41 so that a return of said cams to their former positions will bring the rollers 12 and 29 to their former positions where the screws 14 and 41 will determine the degree of pressure of the rollers 12 and 29 upon the roller 10. By using cams as the actuating means for the throw-off mechanisms, the desired pressure may be developed and rapidity of movement of the rollers 12 and 29 is secured.

If it be found in the operation of the machine that the pressure for which the machine is set is too great, this pressure may be relieved by a slight movement of the cams 19 and 39 or when setting the machine for pressure by means of the screws 14 or 41 the cams may be so set that a pressure may be exerted in excess of that for which the screws 14 and 41 are set by a slight movement of the cams in the direction opposite to that in which they are turned to throw their respective rollers out of engagement with the platen roller.

In a machine made in accordance with my invention adequate lubrication may be secured by means of bearing caps or oil cups, the design of the machine being such as to lend itself to the use of this system of lubrication. Heretofore, in embossing machines, the question of lubrication has been a difficult one. If desired a spraying tube may be used below the tension and guide rollers 48 to dampen the cloth before it passes between the rollers 10 and 12. This is a common expedient in this art, however, and I lay no claim of invention thereto.

It is not my intention to limit the invention to the precise details of construction shown in the accompanying drawings, it being apparent that many of the refinements shown in the drawings may be dispensed with, without departing from the spirit and scope of the invention. I have found it essential to use a counter-pressure roller, the length of which is considerably less than that of the pattern roller and to position this counter-pressure roller so that the stresses therefrom will be applied at and adjacent the center of the said pattern roller and I intend to claim such broadly. I also believe it is broadly new to provide an embossing machine wherein the pressure upon the pattern roller is developed by the movement of the platen roller toward said pattern roller. I also believe it to be new to provide a pressure regulating mechanism in-

cluding therein a throw-off mechanism so that the pressure between the platen roller and the pattern roller may be entirely relieved without disturbing the adjustment for pressure and which may be actuated to substantially instantly restore this pressure.

Having described the invention what I claim as new and desire to have protected by Letters Patent is:—

1. An embossing machine embodying therein a pattern roller mounted in fixed bearings, movable sectional bearings, a platen roller mounted in one of the sections of said bearings, a cam shaft mounted in one of the sections of said bearings, cams carried thereby and acting upon the other section whereby said platen roller may be moved toward or from said pattern roller, feed screws acting upon said bearings respectively, worm wheels carried by said feed screws, a worm shaft co-operating with both of said worm wheels whereby said bearings may be simultaneously advanced and to the same extent toward said pattern roller and independently operative actuating means for said cam shaft and said worm shaft whereby said bearings may be set for a definite pressure and said platen roller may be moved into and out of engagement with the pattern roller without disturbing the said adjustment for pressure.

2. An embossing machine embodying therein a pattern roller, a platen roller, means whereby movement is imparted to one of said rollers relative to the other to develop the required pressure, a counter-pressure roller of short length supported adjacent the center of said pattern roller and means whereby said counter-pressure roller may be forced into engagement with said pattern roller to prevent said pattern roller intermediate its ends springing away from said platen roller.

3. An embossing machine embodying therein a pattern roller, a platen roller, means whereby relative movement is imparted to said rollers to develop the required pressure, a counter-pressure roller of short length supported adjacent the center of said pattern roller and means whereby said counter-pressure roller may be forced into engagement with said pattern roller to prevent said pattern roller intermediate its ends springing away from said platen roller, said last named means including a throw-off mechanism whereby said counter-pressure roller after said means has been set for a definite pressure may be moved toward or from said pattern roller without disturbing said adjustment for pressure.

4. An embossing machine embodying therein a pattern roller, a platen roller, means whereby relative movement is imparted to said rollers to develop the re-

- 6
- quired pressure, a yoke pivotally mounted at one side of the bearings for said pattern roller, a counter-pressure roller pivotally mounted in said yoke above said pattern roller, a projection carried by said yoke and a screw adapted to bear upon said projection and force said counter-pressure roller into engagement with said pattern roller to prevent said pattern roller intermediate its ends springing away from said platen roller.
5. An embossing machine embodying therein a pattern roller, a platen roller, means whereby relative movement is imparted to said rollers to develop the required pressure, a counterpressure roller of short length supported adjacent the center of said pattern roller and means whereby said counterpressure roller may be forced into engagement with said pattern roller to prevent said pattern roller intermediate its ends, springing away from said platen roller, entrained gears carried by the said pattern roller, said platen roller, and said counterpressure roller whereby said rollers are simultaneously rotated at the same peripheral speed and a connection having universal joints between the gear for said counterpressure roller and the shaft of said roller.
25. An embossing machine embodying therein a pattern roller, a platen roller, means whereby relative movement is imparted to said rollers to develop the required pressure, a yoke pivotally mounted at one side of the bearings for said pattern roller, a counter-pressure roller pivotally mounted in said yoke above said pattern roller, a projection carried by said yoke, a rotatable shaft, a yoke pivotally mounted on said shaft, a screw carried by said yoke and adapted to bear upon said projection and force said counter-pressure roller into engagement with said platen roller to prevent said pattern roller intermediate its ends springing away from said platen roller, cams carried by said shaft and co-operating cam housings adjacent the bearings for said shaft whereby the rotation of said shaft in one direction will force the yoke mounted thereupon in one direction to relieve the pressure exerted by said counter-pressure roller and the rotation of said cams in the other direction will move said yoke to develop the pressure for which said screw is set whereby said counter pressure roller may be moved into and out of engagement with said pattern roller without disturbing the adjustment secured by means of said screws.
60. An embossing machine embodying therein a pattern roller mounted in fixed bearings, a movable platen roller, a pressure developing mechanism whereby said platen roller may be moved toward said pattern roller to develop the required pressure, said pressure developing mechanism

including therein an independently operative throw-off mechanism whereby said platen roller after said pressure developing mechanism has been set for a definite pressure may be moved toward or from said pattern roller without disturbing the said adjustment for pressure, a counter-pressure roller of short length supported adjacent the center of said pattern roller, means whereby said counter-pressure roller may be forced into engagement with said pattern roller to prevent said pattern roller intermediate its ends springing away from said platen roller, said last named means including therein a throw-off mechanism whereby said counter-pressure roller after said means has been set for a definite pressure may be moved toward or from said platen roller without disturbing the adjustment for pressure of said counter-pressure roller and independently operative means controlling the throw-off mechanisms for said platen roller and said counter-pressure roller.

8. An embossing machine embodying therein a pattern roller mounted in fixed bearings, a movable platen roller, a pressure developing mechanism whereby said platen roller may be moved toward said pattern roller to develop the required pressure, said pressure developing mechanism including therein an independently operative throw-off mechanism whereby said platen roller after said pressure developing mechanism has been set for a definite pressure may be moved toward or from said pattern roller without disturbing said adjustment for pressure, and means whereby the operative effect of said throw-off mechanism may be varied to vary the pressure independently of said pressure developing mechanism, a yoke pivotally mounted to one side of the bearing for said pattern roller, a counter-pressure roller, a projection carried by said yoke and a screw adapted to bear upon said projection and force said counter-pressure roller into engagement with said pattern roller to prevent said platen roller intermediate its ends springing away from said platen roller.

9. An embossing machine embodying therein a pattern roller mounted in fixed bearings, movable sectional bearings, a platen roller mounted in one of the sections of said bearings, a cam shaft mounted in one of the sections of said bearings, cams carried thereby and acting upon the other section whereby said platen roller may be moved toward or from said roller, feed screws acting upon said bearings respectively, worm wheels carried by said feed screws, a worm shaft co-operating with both of said worm wheels whereby said bearings may be simultaneously advanced and to the same extent toward said pattern roller, independently operative actuating means for

said cam shaft and said worm shaft whereby said bearings may be set for a definite pressure and said platen roller may be moved into and out of engagement with the 5 pattern roller without disturbing the said adjustment for pressure, a yoke pivotally mounted to one side of the bearings for said platen roller, a counter-pressure roller pivotally mounted in said yoke above said pattern roller, a projection carried by said yoke, a rotatable shaft, a yoke pivotally mounted on said shaft, a screw carried by 10 said yoke and adapted to bear upon said projection and force said counter-pressure roller into engagement with said platen roller to prevent said pattern roller intermediate its end springing away from said platen roller, cams carried by said shaft and co-operating cam housings adjacent the 15 bearings for said shaft whereby the rotation of 20

said shaft in one direction will force the yoke mounted thereupon in one direction to relieve the pressure exerted by said counter-pressure roller and the rotation of said cam in the other direction will move said yoke 25 to develop the pressure for which said screw is set whereby said counter-pressure roller may be moved into and out of engagement with said pattern roller without disturbing the adjustment secured by means of said 30 screws.

In witness whereof I have hereunto affixed my signature in the presence of two subscribing witnesses, this 9th day of June, 1916.

HENRY D. SCHMIDT.
